UNITED STATES PATENT OFFICE.

STANHOPE BOAL, OF PIQUA, OHIO.

DESIGN FOR A STOVE.

SPECIFICATION forming part of Design No. 36,198, dated January 27, 1903.

Application filed November 13, 1902. Serial No. 131,271. Term of patent 7 years.

To all whom it may concern:

Be it known that I, STANHOPE BOAL, a citizen of the United States, residing at Piqua, in the county of Miami and State of Ohio, have 5 invented a new, original, and ornamental Design for Stoves, of which the following is a specification.

I have invented a new, original, and ornamental design for heating-stoves, of which the 10 following is a description, taken in connection with the accompanying drawing, which shows an elevation of a heating-stove with my new design applied.

As shown in the drawing, the leading features of my invention consist in the style, 15 form, and ornamentation of the base-frame, the ash-box, and the fire-bowl, arranged one above the other, each section having a horizontal or shelf-like projection symmetrically 20 arranged and ornamented.

The base-frame consists of the marginal frame A and the sloping portion B, the part 25 A having raised ornamentations. The part B is oval shape, sloping outwardly and downwardly with ribs and recesses forming the top surface thereof. The ash-box C, resting on the base, is ornamented around its side.

D represents a shelf-like extension overhanging the ash-box, slightly oval and ornamented with raised figures. The fire-box E is ornamented around the column with ribs and grooves. The top of the fire-bowl F is an overhanging sloping rim ornamented with raised figures. The base, ash-box, and fire-bowl are each of different shape and size, but 30 are made in general appearance symmetrical, the ornamentation of each being distinct from the other and progressively smaller in diameter from the base to the top, giving symmetry to the whole. The feed-door and crown 35 of the stove are shown as ornamented, having oval surfaces; but they are not made a feature of the invention herein.

Having described my invention, what I 40 claim is—

The ornamental design for a heating-stove, 45 as herein shown and described.

In testimony whereof I have hereunto set my hand.

STANHOPE BOAL.
